UNITED STATES PATENT OFFICE.

MAE S. DICKSON, OF HUBBARD WOODS, ILLINOIS.

CAN-OPENER.

1,348,484.

Specification of Letters Patent.

Patented Aug. 3, 1920.

Application filed January 26, 1920. Serial No. 353,918.

To all whom it may concern:

Be it known that I, MAE S. DICKSON, a citizen of the United States of America, and a resident of Hubbard Woods, in the county 5 of Cook, State of Illinois, have invented certain new and useful Improvements in Can-Openers, of which the following is a specification.

This invention relates to that type of can 10 opening implements in which a rocking movement is imparted to the cutter blade to attain a step-by-step circular cut in the top of the can to be opened, and has for its object:—

15 To provide a simple and efficient structural formation and association of parts providing means for effecting an initial puncture opening in the can top, and with which a powerful stress on the cutter plate is attained in a convenient and effective manner 20 to attain a rapid opening of the can, all as will hereinafter more fully appear.

In the accompanying drawing:—

Figures 1 and 2 are perspective views from 25 the respective outer and inner sides of the implement, illustrating the preferred arrangement of parts in the present invention.

Fig. 3 is a rear end elevation.

Like reference numerals indicate like parts 30 in the several views.

Referring to the drawing, 1 designates the bearing plate or member of the instrument, by which bearing is had on the marginal rim of a can in an opening operation 35 of the same. The plate 1 is of a flat rectangular shape and provided at its outer side with a depending flange or ear 2 adapt-

ed to have bearing against the circular periphery of the can and prevent lateral movement of the instrument, in actual use. 40

4 designates the cutter plate preferably formed as an integral and angular extension of the aforesaid bearing plate 1 and formed with an open ended longitudinal slot or throat 3 dividing the plate 4 into a lower 45 cutter member or blade 5 of a pointed form as shown, and into an upper member 6 constituting an integral and angular extension of the bearing plate 1.

7 designates a fixed stem or shank extending away from the top of the bearing plate 1 and carrying a longitudinally arranged hand grip 8, the rear end of which is formed to fit the operator's hand, while the forward end 9 is of a pointed formation adapted to 55 effect a ready initial perforation of the can top, so that an entry of the point of the cutter blade 5 may be made in the operation of opening the can.

Having thus fully described my said invention, what I claim as new and desire to secure by Letters Patent is:—

A can opener of the type described, the combination of a bearing plate carrying guiding and opening means, a stem connected centrally at the mid-length of said plate, and a longitudinally extending hand grip connected at its mid-length to said stem to afford finger grips at each side of the stem, the forward end of the hand grip having a 70 pointed formation.

Signed at Winter Park, Fla., this 21st day of January, 1920.

MAE S. DICKSON.
